(57) **CLAIM**

The ornamental design for a closed vehicle lift arm, as shown and described.

DESCRIPTION

FIG. 1 is a front perspective view of a closed vehicle lift arm, showing our new design.

FIG. 2 is a front left view of the closed vehicle lift arm of FIG. 1.

FIG. 3 is a rear right view of the closed vehicle lift arm of FIG. 1.

FIG. 4 is a front view of the closed vehicle lift arm of FIG. 1.

FIG. 5 is a rear view of the closed vehicle lift arm of FIG. 1.

FIG. 6 is a left side elevation view of the closed vehicle lift arm of FIG. 1.

FIG. 7 is a right side elevation view of the closed vehicle lift arm of FIG. 1.

FIG. 8 is a top view of the closed vehicle lift arm of FIG. 1; and,

FIG. 9 is a bottom view of the closed vehicle lift arm of FIG. 1.

The broken lines showing a vehicle lift assembly and another closed vehicle lift arm in FIG. 1 are for the purpose of illustrating environmental structure, and form no part of the claimed design.
